PRODUCTION OF AN ACID OF THE ASCORBIC ACID TYPE FROM A 2-KETO-HEXONIC ACID

Viktor Ettel, Prague, Czechoslovakia, assignor to Spolek pro chemickou a hutni výrobu, národní podnik, also named United Chemical and Metallurgical Works, National Corporation, Prague, Czechoslovakia

No Drawing. Application May 10, 1949, Serial No. 92,520. In Czechoslovakia May 13, 1948

3 Claims. (Cl. 260—344.5)

1

It is known that 2-keto-hexonic acids, if necessary their esters, can be transformed in alkaline or acid media into corresponding acids of the ascorbic acid type of the composition

The ascorbic acid is characterized by a lactonic ring and an endiol group $\text{COH}=\text{COH}$, which reacts as a dibasic acid, represents the actual acid carrier and whose H-atoms can be replaced by a metal in the formation of salts. Two kinds of ascorbic acid mainly are known, which differ by spatial configuration, namely, (1) l-ascorbic acid physiologically effective as vitamin C, (2) the isoascorbic acid, which is designated by Fischer as follows:

The reaction, by which ascorbic acid is formed from the 2-keto-hexonic acids, occurs by enolisa-

2

The subject of this invention is a method for the enolisation of 2-keto-hexonic acids in alkaline medium in the presence of amphoteric hydroxides of heavy metals, which form compounds with alkalis, as for example, $\text{Pb}(\text{OH})_2$ or $\text{Zn}(\text{OH})_2$, in water-free solvents. The amphoteric heavy metals are used in the form of their alkali compounds of the type $\text{Me}(\text{ONa})\text{OH}$ (Me = amphoteric metal) in a suspension or solution of water-free solvents. In this way the enolisation takes place very rapidly with heating, namely in the course of few minutes, and with good yield. At the same time the ascorbic acid is deposited in the form of difficultly soluble salts of the amphoteric metals, by which means the isolation of this acid in pure state from the reaction mixture is made possible in suitable manner. The method according to the invention is especially suited for the enolisation of difficultly crystallizing esters of the 2-keto-hexonic acids, from which completely pure ascorbic acids are then obtained. Pb - or Zn -salts of the ascorbic acid are disintegrated by the action of H_2SO_4 or H_2S in an organic solvent. The yield in pure substance is 70–80% of the theory. The reaction generally proceeds according to the following scheme:

tion. This represents substantially the rearrangement of an H-atom on to the neighbouring CO - group, a double bond according to the scheme

being formed between the relevant C-atoms (the remaining H-atom can be represented by another group, in this case by the $-\text{OH}$ group).

As is well known the 2-keto-hexonic acids, if necessary their esters, can be transformed into corresponding ascorbic acids by enolisation in alkaline or acid media. In the enolisation with acids furol and other disintegrating products are produced, which decrease the yield of ascorbic acid and render its isolation difficult. On the other hand the enolisation of methyl esters with alkalis in water-free solvents affords much better results, the reaction taking place in shorter time with good yield.

The advantage of the new process for the production of the ascorbic acids lies in the simplified method and the possibility of easier isolation of the acids in the form of insoluble salts of heavy metals, and in the gaining of purer products. A further important advantage of the new process as compared with the hitherto known processes is the increase of the yield of pure substance to 60–70%, instead of the former yield of about 20% of the theory.

Examples of carrying out the process

1. 10 parts of methyl ester of the 2-keto-l-idonic acid (gulonic acid) are dissolved in 100 parts of water-free methanol and enolized with a suspension of 6 parts of sodium zincate $\text{Zn}(\text{ONa})\text{OH}$ in 50 parts of water-free methanol for ten minutes at a temperature of 65°C . in reflux condensation. By the reaction zinc-l-ascorbinate is formed in a yield of 80 to 85%

of the theory. Complete precipitation of the zinc salt is obtained by the cooling of the reaction mixture and addition of 50 parts of ether. The slightly yellow coloured deposit of zinc-l-ascorbinate is suctioned off, suspended moist in 100 parts of water-free methanol and precipitated with an equivalent amount of H_2SO_4 or H_2S . The separated $ZnSO_4$ or ZnS is filtered off and the filtrate concentrated in vacuo at 20° C. 6.2 to 6.5 parts of l-ascorbic acid is obtained, that is a yield of 74 to 77% of the theory. The product recrystallized from methanol has a melting point of 181 to 185° C.

2. 10 parts of methyl ester of the 2-keto-d-gluconic acid are dissolved in 200 parts of water-free methanol, enolized with a suspension of $Zn(ONa)OH$ and treated further according to Example 1. The yield of the isoascorbic acid formed amounts to 75 to 78% of the theory. The pure product recrystallized from methanol melts at 173° C.

3. 10 parts of methyl ester of the 2-keto-l-ionic acid are dissolved in 100 parts of water-free methanol and enolized with a suspension of 13 parts of $Pb(ONa)OH$ in 50 parts of water-free methanol for 15 to 20 minutes at a temperature of 65° C. in reflux condensation. l-ascorbic acid with a yield of 70% of the theory is produced by the enolization, as was established by titration. The separated yellow lead salt is filtered off after the cooling of the reaction mixture, suspended still moist in water-free methanol and precipitated with H_2S or by addition of an equivalent amount of H_2SO_4 . The separated PbS or $PbSO_4$, is filtered and the filtrate containing l-ascorbic acid concentrated in vacuo. The yield of pure substance amounts to 60 to 65% of the theory and its melting point is 180 to 183° C.

4. 10 parts of methyl ester of the 2-keto-d-gluconic acid are dissolved in 200 parts of water-free methanol, enolized with $Pb/ONa/OH$ and treated further as in Example 3. Through the reaction isoascorbic acid is obtained with a yield of 60 to 68% of the theory. The melting point of the recrystallized product is 168 to 170° C.

What I claim as my invention and desire to secure by Letters Patent is:

1. A process for the production of an acid of the ascorbic acid type from a 2-keto-hexonic acid, which comprises enolizing esters of 2-keto-

hexonic acid by heating them in a water-free lower alcohol with an alkali compound of amphoteric hydroxides of heavy metals selected from the group Pb and Zn treating this precipitate of a metal salt of ascorbic acid with a substance selected from the group consisting of hydrogen sulphide and sulphuric acid, filtering to obtain a filtrate containing soluble ascorbic acid, concentrating the filtrate, and working up the concentrate to pure ascorbic acid.

5. A process for the production of an acid of the ascorbic acid type from a 2-keto-hexonic acid, which comprises enolizing esters of 2-keto-hexonic acid by heating them in a water-free lower alcohol with an alkali compound of amphoteric hydroxides of heavy metals selected from the group Pb and Zn, treating this precipitate of a metal salt of ascorbic acid with a substance selected from the group consisting of hydrogen sulphide and sulphuric acid, filtering to obtain a filtrate containing soluble ascorbic acid, concentrating the filtrate, and working up the concentrate to pure ascorbic acid.

15. A process for the production of an acid of the ascorbic acid type from a 2-keto-hexonic acid, which comprises enolizing esters of 2-keto-hexonic acid by heating them in a water-free lower alcohol with an alkali compound of amphoteric hydroxides of heavy metals selected from the group Pb and Zn, treating this precipitate of a metal salt of ascorbic acid with a substance selected from the group consisting of hydrogen sulphide and sulphuric acid, filtering to obtain a filtrate containing soluble ascorbic acid, concentrating the filtrate, and working up the concentrate to pure ascorbic acid.

20. A process for the production of an acid of the ascorbic acid type from a 2-keto-hexonic acid, which comprises enolizing esters of 2-keto-hexonic acid by heating them in a water-free lower alcohol with an alkali compound of amphoteric hydroxides of heavy metals selected from the group Pb and Zn to precipitate a heavy metal salt of ascorbic acid, treating this precipitate with a substance selected from the group consisting of hydrogen sulphide and sulphuric acid, filtering to obtain a filtrate containing soluble ascorbic acid, concentrating the filtrate in vacuo at a low temperature, and working up the concentrate to pure ascorbic acid.

VIKTOR ETTEL.
